UNITED STATES PATENT OFFICE.

NORMAN W. STORER, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTING DEVICE.

1,374,534.

Specification of Letters Patent. Patented Apr. 12, 1921.

Application filed January 6, 1917. Serial No. 140,920.

To all whom it may concern:

Be it known that I, NORMAN W. STORER, a citizen of the United States, and a resident of Pittsburgh, in the county of Allegheny and State of Pennsylvania, have invented a new and useful Improvement in Circuit-Interrupting Devices, of which the following is a specification.

My invention relates to means for, and methods of, automatically interrupting electrical circuits, under predetermined conditions.

One object of my invention is to provide an automatic circuit interrupter having no movable parts.

Another object of my invention is to provide means whereby the current traversing a circuit may be reduced to a safe value when an overload or short circuit occurs thereon that tends to produce a surge of current.

A further object of my invention is to provide a device, of the above indicated character, that shall be effective and reliable in its operation and simple to construct.

In the carrying out of my invention, I provide a vacuum-electric apparatus, such as a mercury-vapor valve or converter, and a transformer the primary winding of which is connected in series with the valve and the electric circuit. The secondary winding of the transformer is adapted to have a smaller number of turns than the primary winding and is connected in series with a current-limiting resistor, and the circuit, thus constituted, is connected in shunt relation to the valve. Under normal conditions, since the device is used in connection with a direct-current circuit, no voltage is induced in the secondary winding. However, when a short circuit or an overload occurs on the circuit, the primary winding will cause the current to be shunted from the valve to extinguish its arc and to establish a relatively high-resistance path for the current for the purpose of reducing it to a safe value.

In the accompanying drawings, Figure 1 is a diagrammatic view of an electrical circuit embodying my invention, and Fig. 2 is a diagrammatic view of a modified form of electric circuit embodying my invention.

A direct-current circuit 1 comprises, in general, a generator 2 or other source of

electromotive force, an interrupting device 3 and a load 4.

The interrupting device 3 comprises a vacuum-electric apparatus 5 such as a mercury-vapor valve or converter, a transformer 6 having a primary winding 7 that is connected in series with the valve 5, a magnetizable core member 8 having an air gap 9 therein and a secondary winding 10. An adjustable current-limiting resistor 11 is connected in series with the winding 10 and the circuit, thus constituted, is connected in shunt relation to the valve 5 in such manner that it normally tends to force current through the valve in a direction opposite to the normal direction of flow therethrough.

The winding 10 has a smaller number of turns of less resistance than the winding 7. Thus, when the current that traverses the circuit 1 changes quickly because of a ground or short-circuit thereon, substantially all of the current that traverses the circuit will be caused to flow through the resistor 11. However, since the resistor 11 and the winding 10 are connected in shunt relation to the valve 5 in a manner as hereinbefore set forth, when this condition obtains, insufficient current will traverse the valve 5 to maintain its arc. Thus, the arc in the valve 5 will be extinguished and a relatively small current will traverse the winding 10 and the circuit 1, because of the presence of the resistor 11.

If it is desired to use my circuit-interrupting device in connection with a direct-current circuit in which energy is regenerated, I provide two parallel-connected oppositely-disposed vacuum-electric devices 12 and 13, substantially as shown in Fig. 2 of the drawings. The valves 12 and 13 are so arranged that current, traversing the circuit 1 in the normal direction, will traverse the valve 12, and the regenerated current will traverse the valve 13. By this arrangement, the current that traverses the circuit in the normal direction may be limited by the resistor 11, substantially as hereinbefore set forth, when an overload or other disturbance upon the circuit causes the current traversing the same to change quickly, and a substantially unobstructed path is provided for the regenerated current to traverse the circuit.

I do not limit my invention to the par-

ticular structures illustrated, as it may be variously modified without departing from the spirit and scope of the invention, as set forth in the appended claims.

5. I claim as my invention:

1. In an electric circuit, the combination with a vacuum-electric apparatus normally traversed by current in one direction, of a transformer the primary winding of which is connected in series with the vacuum-electric apparatus, a resistor connected in series with the secondary winding of the transformer, the circuit thus constituted being so connected in parallel relation to the vacuum-electric apparatus as to tend to force current therethrough in the incorrect direction.
10. is connected in series with the vacuum-electric apparatus, a resistor connected in series with the secondary winding of the transformer, the circuit thus constituted being so connected in parallel relation to the vacuum-electric apparatus as to tend to force current therethrough in the incorrect direction.
15. 2. In a electric circuit, the combination with an asymmetric valve connected in series with the circuit and normally traversed by current in one direction, of a transformer the primary winding of which is connected in series with the valve and the secondary winding of which is so connected in shunt relation to the valve as to tend to force current therethrough in the incorrect direction.
20. 3. In an electric circuit, the combination with an asymmetric valve, of a transformer the primary winding of which is connected in series with the valve and the secondary winding of which is so connected to the valve that, when the current traversing the circuit changes quickly, the same is shunted around the valve to render the same inoperative.
25. 4. In an electric circuit, the combination with an asymmetric valve normally traversed by current in one direction, of a transformer the primary winding of which is connected in series with the valve and the secondary winding of which is so connected in shunt relation to the valve as to tend to force current therethrough in the incorrect direction.
30. 5. In an electric circuit, the combination with a vapor valve, of a transformer the primary winding of which is connected in series with the valve, and a resistor connected in series with the secondary winding of the transformer, said resistor and secondary winding being so proportioned and so connected to the valve that, when the current traversing the circuit changes quickly, sufficient current will be shunted around the valve to extinguish its arc.
35. 6. In an electric circuit, the combination with a plurality of oppositely-disposed parallel-connected vapor valves, of a trans-
- former the primary winding of which is connected in series with the valves and the electric circuit, and a resistor connected in series with the secondary winding of the transformer, said resistor and secondary winding being connected in shunt relation to the valves in such manner as to tend to cause one of the valves to have an opposite polarity.
40. 7. In a direct-current circuit, the combination with a vapor valve therein, of a transformer, and means for so connecting the transformer to the valve that, when the current traversing the circuit changes quickly, sufficient current will be shunted around the valve to extinguish its arc.
45. 8. In an electric circuit, the combination with a vapor valve, of a transformer, a resistor, and means for so connecting the transformer and the resistor to the valve that, when the current that traverses the circuit changes quickly, sufficient current will be shunted around the valve to extinguish the arc, and the resistor will be inserted in the circuit to reduce the current traversing the valve.
50. 9. In a direct-current circuit, the combination with a vapor valve connected in series with the circuit, of a resistor, and inductive means so connected to the resistor and to the valve as to shunt the current around the valve to extinguish its arc when the current traversing the circuit changes quickly and to reduce the current traversing the circuit.
55. 10. In a direct-current circuit, the combination with a vacuum-electric apparatus connected in series with the circuit, of means connected to the circuit and to the said apparatus for extinguishing the arc of the vacuum-electric apparatus when the current traversing the circuit changes quickly and for reducing the current traversing the circuit.
60. 11. The method of reducing the current traversing an electrical circuit, which consists in shunting the current around a mercury-vapor device connected in the circuit by inducing the current to traverse a relatively high-resistance path in shunt relation to the mercury-vapor device only when the current traversing the circuit changes quickly.
65. 12. In testimony whereof, I have hereunto subscribed my name this 28th day of Dec., 1916.

NORMAN W. STORER.
